HOISTING CRANE

Leo Edmond Huot, Newport, Wash.

Application December 28, 1934, Serial No. 759,543

3 Claims. (Cl. 212—46)

My present invention relates to an improved hoisting crane of the portable type, which, while adapted for various uses, is especially designed for use in logging operations, where the logs are picked out of the timber-area and loaded upon trucks, trailers, or other vehicles, for transportation purposes. In carrying out my invention I employ an automotive truck upon which the crane is mounted, and the portable implement is driven into the timber-area for loading operations. In most instances, the surface of the ground is rough and irregular, and consequently, for efficient operations, means are provided for leveling the vehicle or for erecting the boom with its axis of rotation in perpendicular position. I provide, in combination with the upright mast, a boom having upper and lower supports on the mast, and means are provided whereby the axis of rotation of the boom may be plumbed to perpendicular position, to compensate for irregularities on the ground surface on which the truck is standing. Means are also provided for retaining the hinged or pivoted mast, and its supports for the boom, after the adjustments have been made, and means are provided in combination with the hinged mast and its swivel-supported boom, to insure a maximum, available length of the hoisting or hauling cable, in order that remotely located, as well as closely located logs may be handled with facility from a single set-up.

Other means and devices are also employed to insure a loading rig of the portable type, for handling logs with rapidity, facility, and accuracy, thus economizing in expenditure of time and services in the logging operations.

The invention consists in certain novel combinations and arrangements of parts as will hereinafter be more fully set forth and claimed. In the accompanying drawings I have illustrated one complete example of the physical embodiment of my invention wherein the parts are combined and arranged according to one mode I have thus far devised for the practical application of the principles of my invention.

Figure 1 is a view in side elevation of the portable crane, anchored to tree-stumps, and in position to haul, hoist, and deposit the logs in a waiting truck or other vehicle usually located at one side of the crane.

Figure 2 is a view in elevation at the rear of the mast, looking from the front of the automotive truck.

Figure 3 is a side elevation of the portable crane, with parts folded to position for transportation.

Figure 4 is a top plan view of the crane, anchored to three tree-stumps, and in position to haul or drag logs from the front and left side of the crane.

Figure 5 is an enlarged detail sectional view at 5 the lower, swiveled end of the boom, showing the travel of the haul or hoist cable past the swiveled joint between the boom and its mast.

Figure 6 is a top plan view of part of Figure 5, as at lines 6—6.

Figure 7 is a view in side elevation of the upright or perpendicular mast, the mast being cut through on line 7—7 of Figure 2 to illustrate parts in section.

Figure 8 is a detail sectional view at line 8—8 15 of Figure 7.

In the general assembly views of Figures 1, 3, and 4, I have illustrated the portable crane mounted upon an automotive truck A, which has the usual frame F, and is equipped with a cross sill S mounted transversely of the frame F at the approximate center of weight of the vehicle. The hinged or pivoted mast M is mounted on the sill, and when in operative position, the mast is anchored to conveniently located tree stumps as 25 T and T' at the front of the automotive truck, while the boom B, swiveled on the mast, is stayed against lateral swing to the left in Figure 4, by a tree-stump T².

The mast M, which is of A-shape, is hinged or pivoted on bolts 1, 1, extending transversely of the vehicle A, and these bolts are housed or journaled in brackets or journal bearing blocks 2, 2, securely bolted on the top of the transverse sill S.

At its lower end, but above the hinge joint, the mast is provided with a beam 3 extending transversely of the automotive truck, and above the sill S, and the corner edges of the beam are equipped with angle iron edge-strips 4 for use as 40 wear faces in combination with a laterally slideable carriage or saddle 5 upon which the boom is supported, and by means of which the aligned axial supports for the boom are plumbed to perpendicular position, when the vehicle A is not 45 level.

The slide saddle or carriage is fashioned with guide flanges 6, 6, at the rear of the beam 3, for sliding contact with the wear plates 4, 4, and as shown best in Figure 5, the saddle extends across 50 the top and bottom faces of the beam and also across the front face of the beam, the wear plates at the corners of the beam furnishing a rigid support for the slideable saddle.

The adjusting slide-saddle is moved laterally, 55

- or transversely of the truck A, through the instrumentality of a traveling nut 7 that is rigidly bolted to the slide saddle. An adjusting screw bar 8 is journaled in bearings 9, and is threaded through the nut, a handle wheel 10 being mounted on one end of the bar for turning the latter, to feed the nut and saddle transversely of the vehicle, but longitudinally of the supporting beam 3.
- 10 On the front face of the adjusting saddle are rigidly mounted a pair of vertically aligned bearing blocks 11, 11 in which the upper and lower journal-ends of the swivel pin 12 are journaled, and this pin, which supports the boom in position to swing laterally in front of the mast, is fashioned with a fixed collar 13 that encircles the intermediate portion of the pin. A bearing yoke 14 rigid with the swivel pin and collar 13 projects forwardly of the pin, and a pair of spaced pivot-plates 16, 16, bolted at opposite sides of the end of the boom are located exterior of the yoke, so that a pivot bolt 15 may be passed through aligned holes in the walls of the yoke and the two plates, in order to permit the boom 25 to swing in a vertical plane with the bolt 15 as a center.
- 15 The hoist line 17, which is employed to drag or haul the logs, then hoist them, and finally to drop or deposit them in a vehicle, in its travels, is brought to the swivel joint between the boom and the mast, and from the free end of the boom this line or cable passes through a hole in the front of the yoke, thence under a guide pulley 18 journaled on the hinge bolt 15, thence upwardly through a recess 19 in the front portion of the swivel pin, and then upwardly through an axially aligned guide hole 20 extending longitudinally of the pin from the recess to the upper end of the pin. Spaced at diametrically opposite points about the hole 20 are a pair of grooved guide pulleys 21, 21 between which the hoist line 17 passes. These two guide pulleys are journaled at 22, 22 in flanges of a plate 22' attached at the top of the slide, and forming a rigid part thereof. From the pair of guide pulleys 21 the hoist line 17, after passing under the swivel pulley 18, extends out along the boom and through a pulley 23 suspended at the free end of the boom, and a fastening hook 24 is provided at the end of the hoist line for securing to the chain usually wrapped around the log.
- 20 The winding end of the hoist line passes from the two guide pulleys, up the mast, and over a guide pulley 25 that is suspended by the swivel bolt 26 from the top of the mast, thence downwardly to the hoist windlass or drum 27 mounted on the frame F of the automotive truck, and provided with the usual control and operating means whereby the line is wound and permitted to unwind on and off the drum.
- 25 The free ends of the mast and boom are flexibly connected by means of a permanently coupled cable 28, attached to the mast at 29, and to the boom at 30.
- 30 For proper and efficient operation of the crane, it is necessary that the upper supporting point 29 and the axis of the swivel pin 12 shall be aligned perpendicular to the ground surface, otherwise the boom will have a tendency to swing laterally.
- 35 If the ground surface is irregular, causing a lateral tilt, or lateral leaning of the mast, thereby swinging the axial line of the supports of the boom out of perpendicular, this defection is compensated for by sliding the saddle and swivel-head, transversely of the truck A, to plumb the

line to a perpendicular position, and the reach of cable 17 between the pair of guide pulleys 21, 21 and the guide pulley 25 is also brought to perpendicular position.

By this zig-zag arrangement of the four reaches of the hoist line 17, a long stretch of the cable is available for use, and the reach from the outer pulley 23 to the hook 24 may be drawn out to considerable length for attachment of the hook 24 to the chain of a log located a substantial distance from the crane. After the hauling reach has been shortened by dragging the log toward the crane and winding the hoist line on the drum or windlass, the log is hoisted from the ground, and then deposited in a waiting truck, trailer, or other vehicle.

After the boom supports have been properly adjusted, the mast is guyed or braced with cables or guy lines 31 and 32 wound upon the reels 33, 33, one mounted at the outer side of each leg of the A-shaped mast. From these reels the guy lines or cables 31 and 32 pass upwardly over guide pulleys 34 that are provided with swivel supports from the top bolt 26 of the mast, and located at opposite sides of the mast. From these guide pulleys 34, 34 the guy cables pass back to the two tree stumps T and T', selected as anchors at opposite sides of the front end of the truck A.

A front lateral guy, or forward brace for the boom is provided in the use of a cable 35, which is wound on the reel 36 mounted on the boom B, near its swivel end, and the outer, free end of this guy may be fastened, as an anchor, to a tree stump T², forward of the crane and to one side thereof. The guy 35 and tree stump T² form an anchoring means to limit the swing of the boom to the left in Figure 4, and to resist strains and stresses when a log is being dragged or hauled at the hook-end 24 of the hoist line in Figure 4. The length of this guy cable may readily be adjusted by means of the reel, and the location of the anchor T² may be selected as desired, the guy cable, which passes through guide pulley 37 at the free end of the boom, being payed out, or reeled in, as required.

The upright mast M is held in upright position in connection with an upright-frame 38, imposed on the top of the frame F of the automotive truck, and the mast is provided with a rigid cross-head 39, in the nature of a channel plate attached at its opposite ends to the legs of the mast. A stop bolt 40 is mounted, in horizontal position in the upright frame, just back of the cross-head 39 of the mast, and the cross head contacts with the head of the bolt to prevent swinging of the hinged mast to the rear, beyond its upright position. This stop bolt is adjustable with relation to the cross head and it slides in a housing 41 mounted on the upright frame. The bolt is fashioned with a rack-portion 40' and a hand-operated rack 42 journaled in the housing, may be turned by the crank handle 43 to adjust the slide bolt with relation to the cross head.

Retaining chains 44 are coupled at each end of the cross head 39 and are adapted to be attached by a link at or near their free ends, to hooks 46 mounted on the upright frame for the purpose of holding the mast against the stop bolts 40 to prevent swinging of the mast in its hinges during the loading operations. Further, in cases where the truck is disposed upon an incline forward or backward a true vertical relationship between sheaves 18 and 25 may be maintained by adjusting the upper end of the mast forward or aft in relation to the frame F.

by the use of the stop bolts 40 and chains 44.

A grab hook 47 is suspended from a swivel bolt 45 mounted in the cross head 39 and this hook is utilized in raising the mast and boom from the lowered position of Figure 3 to the elevated and operating position of Figure 1. For raising the crane, the free end of the hoist line 17 is looped and secured around the boom at approximately the position of the collar 50 thence passing over guide pulley 23, under sheave 18, and over the fulcrum pulley 25 whence it is hooked into grab hook 47 and then to the windlass 27. Power applied to windlass 27 winds the line upon the drum, shortening the amount of cable threaded over the pulley arrangement causing the mast to raise a suitable distance. Guy cable 28 is then connected with the free ends of the boom and mast so that continued turning of the windlass will swing both the boom and mast to relative operative positions.

A bunk 48 is arranged transversely at the rear of the automotive truck A for support of the lowered mast and boom, and after the retaining chains 44 have been disconnected from hooks 46, the free end of the hoist line is looped around the boom adjacent collar 50 and the hoisting line is further engaged in grab hook 47 and the mast and boom may be lowered to the bunk by paying out the cable from the windlass 27.

30 In Figure 1 a stay chain 49 is illustrated as attached at one end 50 to the boom, and at its other end the chain is attached at 51 to the frame F of the automotive truck, for the purpose of limiting the lateral swing of the boom on its swivel pin 12.

35 Thus it will be apparent that by means of the adjustable stop bolt 40 and its ratchet or rack operating means, and the chains 44, the mast may be swung to upright position in order that, as viewed in Figure 7, the axis of the pivot pin 12 and the swivel bolt 26 at the top of the mast, are vertically aligned, with the reach of the hoist line 17 between these two points in a vertical plane, to insure proper longitudinal adjustment of the mast.

40 By means of the slide saddle or carriage 5 upon which is mounted the pivot pin 12, the pivot end of the boom may be adjusted laterally to bring it into a perpendicular line with the swivel bolt 26 at the head of the mast.

45 In some instances it is desirable that the boom may be permitted to swing laterally, under action of gravity, thereby aiding in swinging an uplifted log, or in aiding in hauling a log across the ground. Thus, the slide saddle may be adjusted to one side of the perpendicular line of the

swivel bolt 26 at the mast-head, causing a tendency to tilt on the part of the boom. Under these conditions the boom will naturally swing toward the side of the automotive truck opposite to that of the pivot pin 12 to assist in moving the loaded boom. The unloaded boom, with its lighter weight, may then be swung back again to loading position. The natural swing of the boom, under these conditions, is controlled by the use of the stay chain 49 that couples the boom with the rear part of the truck, and the chain is adjustable for limiting the swing of the boom.

5 The usual control line (not shown) may be attached to the free end of the boom, and manipulated by a ground-man for swinging the boom 15 on its pivot.

Having thus fully described my invention, what I claim as new and desire to secure by Letters Patent is:

1. The combination in a crane with an upright 20 frame and a hinged mast, of a housing rigid with the mast, a rack bar mounted in a housing and a rack wheel therefor, a cross-head on the mast for contact with the bar to limit rearward swing of the mast, and a chain connecting said cross head 25 and frame to limit forward swing of the mast.

2. The combination in a portable crane, with its carrier and an upright frame rigid with the carrier, of a mast having a hinge supported on and extending transversely of the carrier, an 30 adjustable stop mounted on the frame to limit rearward movement of the mast, a flexible coupling between the mast and the frame to limit forward movement of the mast, a boom having an adjustable pivotal support on the mast, means 35 for laterally adjusting said support between points at the opposite sides of the perpendicular center of the mast, and a cable connecting the free ends of the mast and boom.

3. The combination in a portable crane with 40 its carrier, of a mast having spaced aligned hinges supported on the carrier and a transverse base member above the line of the hinges, a laterally adjustable saddle mounted on the base member between the hinges and means for adjusting 45 the saddle, an upright swivel-pin having an opening therein and mounted at the front of the saddle, a pulley having a horizontal journal-pin mounted at the front of the swivel-pin, a boom pivoted on the journal pin, a hoist line for the 50 boom passing around the pulley and through said opening, and a coupling cable attached at one end to the free end of the boom and attached at its other end to the mast.

55 LEO EDMOND HUOT.
